UNITED STATES PATENT OFFICE

JEREMIAH CARR FORSTER, OF FORESTBURG, ALBERTA, CANADA

BUILDING INSULATOR

Application filed January 14, 1930. Serial No. 420,741.

This present invention relates to new and useful improvements in a building insulator and has for its primary object the provision of an improved and simple form of insulator which may be used in the wall, floor or roof structure of a building to insulate the same by forming air pockets therein.

Another object of the invention resides in the provision of a simple form of insulator which is produced in a single blank without waste of material and which is readily folded to compact form and positioned between parallel members of the building structure with turned out longitudinal edges of the insulator blank secured on the outer face of two of said parallel members.

A further object of the invention resides in the provision of a building insulator of the character stated which is produced from a single rectangular blank without waste of material and scored or marked to indicate the manner of folding the blank for positioning the same in the frame work of the building structure for forming dead air or vacuum pockets therein while the longitudinal edges of the blank are secured on the face of the frame member, outside of the pockets.

A still further object of the invention resides in the provision of a building insulator of the character stated which is constructed from a blank without waste of material and is cut and scored in such a manner that it is snugly engaged in the spaces between the frame members of the building structure with the longitudinal strips at the sides of the blank engaging the edges of the frame members while the transverse strips at the ends of the blank are folded in the spaces with their extended free extremities turned at a right angle and resting in the dead air or vacuum pocket formed by the insulator.

A still further object of the invention resides in the provision of a building insulator of the character stated which may be used in any portion of the frame work of the building and may be readily secured in position or removed, as desired.

The invention has for a still further object the provision of a building insulator of the character stated which may be manufactured

at small cost from an appropriate material such as stiff paper, cardboard or other appropriate material, specially treated or otherwise and which may be transported or stored in blank form, without loss or waste of space.

To the accomplishment of these and related objects as shall become apparent as the description proceeds, my invention resides in the construction, combination and arrangement of parts as shall be hereinafter more fully described, illustrated in the accompanying drawings and pointed out in the claim hereunto appended.

The invention will be best understood and can be more clearly described when reference is had to the drawings forming a part of this disclosure, wherein like characters indicate like parts throughout the several views.

In the drawings:—

Figure 1 is an elevation of the blank from which the building insulator is formed;

Figure 2 is a fragmentary perspective, partly in section showing the folding of the blank at the corners thereof;

Figure 3 is a transverse section through a building structure with the improved building insulator incorporated therein; and

Figure 4 is a fragmentary section at right angles to Figure 3 and showing clearly the manner of securing the building insulator in position.

Referring more in detail to the drawings, it will be noted that the blank 6 is of elongated form and has a right angle cut 7 at each corner. The main portion of the blank 6 serves as the body of the building insulator and the blank has a pair of parallel creases or score lines 8 along each side and at which points the blank may be folded to produce the long side members 9 which are of substantially right angular form in cross section. The blank 6 also has a transverse crease or score line 10 adjacent each end and parallel therewith so that the end members 11 may be bent at a right angle to the body of the blank 6, and the free extremities 12 of the ends 11 turned in against the inner angles 9a of the side members 9. The lines of scoring or creases 10 meet the inner lines of scoring or creasings 8, at the inner ends of the cut 7. It will be

apparent that the free extremities of the side members 11 extend past the end members 11 when the blank 6 is folded to produce the building insulator. It is also seen that this building insulator may be constructed from stiff cardboard or the like, either treated or untreated, without any waste of material whatsoever and for shipping or storing purposes, the blanks may be left flat.

5 As the construction of the device has thus been described in detail, brief reference is had to its use and modus operandi: The building insulator is adapted for use in floor structures, wall structures or roof structures and when employed in either structure may be used from either side to form an insulator air pocket or vacuum space between two of the main members of the structure. When used in a floor structure, the insulator is positioned longitudinally between two of the joists and will extend the length as well as the width of the space therebetween with the out-turned portions of the side members 9 of the insulator engaged on the narrow edge of 10 the joists. The insulator may be secured in position by appropriate fastening members 14 extended therethrough and into the joists. The fastening members 14 may be first extended through retaining strips 15, positioned 15 against the end members 11 and against the inner portions of the side members 9, also, if desired, before being passed through the insulator and into the joists and the floor members connecting the latter. When the insulator is employed in a wall structure, it is similarly positioned between adjacent studs and secured thereto in a like manner. Likewise, when the insulator is employed in a roof structure, it is applied between adjacent 20 rafters and secured in position in the manner corresponding to that specifically set forth for incorporating the insulator in a floor structure.

25 Wherever used in a building structure, the insulator forms a pocket which is effectively closed and reinforced at the corners thereof and thus serves to provide a completely closed pocket when the floor, wall or roof structure is finished, so as to effectively 30 insulate the structure.

From the foregoing description, taken in connection with the accompanying drawings, it will be manifest that a building insulator is provided that will fulfill all the necessary 35 requirements of such a device, but as many changes could be made in the above description and many apparently widely different embodiments of my invention may be constructed within the scope of the appended 40 claim without departing from the spirit or scope thereof, it is intended that all matters contained in the said accompanying specification and drawings, shall be interpreted as 45 illustrative and not in a limited sense.

Having thus described my invention, what I claim as new and desire to secure by Letters Patent is:—

A building insulator including the combination with a pair of upstanding parallel main structure members and a pair of transverse parallel main structure members connecting the upper and lower ends of said upstanding parallel main structure members; of a blank having side members and end members formed thereon without waste of material; said side members and end members being adapted to be bent at right angles to the main portion of the blank and against the opposed inner faces of the adjacent transverse parallel main structure members, with the free extremities of the end members turned in against the side members and the latter having outwardly bent edges for engagement on the narrow edges of the upstanding parallel main structure members with which they are engaged and the free extremities of the outwardly bent portions of said side members extended past the folded-in end members of the blank.

In testimony whereof I hereunto affix my signature.

JEREMIAH CARR FORSTER. [L. S.]
